(57) **CLAIM**

The ornamental design for a riding saddle, as shown and described.

DESCRIPTION

FIG. 1 is a perspective view of a riding saddle showing my new design;

FIG. 2 is a front view thereof;

FIG. 3 is a rear view thereof;

FIG. 4 is a right side view thereof; and,

FIG. 5 is an enlarged detail view taken from another perspective of the rear portion of the riding saddle shown in FIG. 1.

The broken lines in the figures illustrate portions of the riding saddle that form no part of the claimed design.
